SPECIFICATION forming part of Design No. 20,281, dated November 11, 1890.

Application filed October 10, 1890. Serial No. 367,633. Term of patent 3½ years.

To all whom it may concern:

Be it known that I, HENRY W. PARTON, a citizen of the United States, residing at Yonkers, Westchester county, New York, have invented a new and original Design for Carpets, of which the following is a specification, reference being had to the accompanying photograph, which forms a part of the same.

The accompanying photograph is a face view of a carpet showing my new design.

My design consists of the body A and the border B. The body A is composed of a group of conventionalized leaf and flower-forms with extending branches ornamented with conventionalized leaf and bud forms. The border B is composed of a double inner

margin of gem-shaped ornamentations, a middle portion having a large group of leaf and flower forms with extending branches ornamented with conventionalized leaf and bud forms and smaller groups of conventionalized flower forms, and an outer margin of wavy bands of gem-shaped ornamentations.

What I claim as new, and desire to secure by Letters Patent, is—

1. The design for carpets, consisting of the body A, substantially as shown.

2. The design for carpets, consisting of the border B, substantially as shown.

3. The design for carpets, consisting of the body A and the border B, substantially as shown.
